UNITED STATES PATENT OFFICE.

CHARLES A. KNILL, OF BELOIT, WISCONSIN.

POLISHING-WHEEL.

SPECIFICATION forming part of Letters Patent No. 683,123, dated September 24, 1901.

Application filed September 6, 1900. Serial No. 29,124. (No model.)

To all whom it may concern:

Be it known that I, CHARLES A. KNILL, a citizen of the United States, residing at Beloit, in the county of Rock and State of Wisconsin, have invented certain new and useful Improvements in Polishing-Wheels, of which the following is a specification.

This invention relates particularly to polishing-wheels having a pneumatic-cushioned peripheral polishing-surface, and has for its object improvements in the manner of providing the pneumatic cushion, of securing the same upon the periphery of the wheel, and to features of construction more fully set forth hereinafter.

In the accompanying drawings, Figure 1 is a side view of a polishing-wheel embodying the features of my invention, portions of the periphery of said wheel being broken away to show its structure. Fig. 2 is a side elevation of the metallic body portion of this polishing-wheel, showing the helical groove in its face for the reception of the pneumatic tube. Fig. 3 shows the body portion represented in the preceding figure, with the pneumatic tube lying in the helical groove formed upon the peripheral face of said body portion. Fig. 4 is a transverse diametric section through the periphery of this polishing-wheel. Fig. 5 is a face view of the emery band intended to encompass the wheel. Fig. 6 is a fragmental view of the pneumatic tube, showing the tapes in the interior thereof.

Like letters of reference indicate corresponding parts throughout the several views.

In the construction of this polishing-wheel I provide the body portion A, formed in this instance of cast-iron, having the hub A', the web A², and the rim A³. In the peripheral face of the rim I turn the semicircular helical groove A⁴, at its ends communicating with the inner side of the rim by means of the openings A⁵ and A⁶, extending through the rim at opposite edges thereof. Each edge of the rim A³ is provided with the annular ring A⁷, secured to said rim by screws A⁸. A pneumatic tube B, in this instance composed of rubber, lies in the helical groove A⁴, each end of said tube being provided with an air-valve B', of the usual construction, extending through the openings A⁵ and A⁶. To pre-

vent the undue stretching and the "creeping" of said tube in its helical groove and to secure the tube in its position upon the face of the wheel A, I insert the tape B² in said tube throughout the length of the latter and secure the ends of the tape to the air-valves B'. An endless cover C, of canvas or other suitable material, surrounds the wheel, covering and protecting the air-tube B. The edges of the cover are provided with openings C' for the passage of the screws A⁸, by means of which latter passing through the ring A⁷ the canvas cover C is secured in its place upon the wheel. The polishing-band D, an endless ring of fabric treated with an abrasive material, is adapted to be slipped over the canvas cover C and is held in position upon said cover by the inflation of the tube B. When the tube is deflated, the polishing-band may be slipped off and on with ease. When it is inflated, the band is retained firmly in its place at the periphery of the wheel. Access to the tube is had by removing the ring A⁷ and slipping the canvas cover C from over the tube. In use the cover is put in place and secured in position by the ring A⁷ and the screws A⁸, the polishing-band D put in place around the cover C, and the tube B inflated by means of an air-pump. When it is desirable to remove the polishing-band, the tube B is deflated. It is evident that a wire or cord might be used for the same purpose as the tape within the tube B or said tube secured to the face of the wheel by cement or other means without departing from the spirit of my invention.

I claim as my invention—

1. In a polishing-wheel, in combination, a body portion; an air-tube on the periphery thereof; and a tape of a constant length, fixed at its ends with relation to said body portion, and adapted to engage said tube and hold the same firmly against the periphery of said body portion.

2. In a polishing-wheel, in combination, a body portion; an air-tube helically arranged on the face thereof; a tape fixed at its ends with relation to said body portion, which tape extends through said air-tube and is of a constant length just sufficient to encircle the body portion thereof and thereby hold said

tube firmly against the periphery thereof; and a polishing-band adapted to lie upon said air-tube.

3. In a polishing-wheel, in combination; a body portion comprising a rim having a helical groove in the peripheral face thereof, and an opening through said rim near each end of said groove; an air-tube in said groove; a tape fixed at its ends with relation to said body portion, which tape extends through said air-tube and is of a length just sufficient

to encircle the body portion and thereby hold said tube firmly against the periphery thereof; an air-valve for each end of said air-tube, which valves extend through said openings 15 in said rim; a cover for said air-tube; and an endless polishing-band.

CHARLES A. KNILL.
